CLAIM

The ornamental design for a workstation screen, as shown and described.

DESCRIPTION

FIG. 1 is a perspective view of the workstation screen; FIG. 2 is a front elevational view of the workstation screen; FIG. 3 is a rear elevational view of the workstation screen; FIG. 4 is a left side elevational view of the workstation screen

FIG. 5 is a right side elevational view of the workstation screen;

FIG. 6 is a top plan view of the workstation screen; and, FIG. 7 is a bottom plan view of the workstation screen. The broken line shown in the drawings are for illustrating portions of the workstation screen that form no part of the claimed design.
